OUTSIDE SUPPORT OR SCAFFOLD FOR
WINDOW CLEANERS AND THE LIKE

Patrick L. Shea, Buffalo, N. Y.

Application November 29, 1949, Serial No. 129,947

3 Claims. (Cl. 304—24)

1

This invention relates to a portable outside support or scaffold for window cleaners and the like which is adapted to support a person exteriorly of a window so that the window may be cleaned, painted, or puttied and other operations such as the placing and removing of screens and storm windows may be accomplished with ease and safety.

An important object of the present invention is to provide such a portable support or scaffold which is completely safe, which is secured firmly in place outside a window before the person using it enters the same, and which cannot be removed or displaced while the occupant is supported thereby.

Another object of the invention is to provide such a support which is light in weight and which can be readily moved through the window into and out of operative position.

A further object of the invention is to provide such a portable support or scaffold which is adapted for use with windows of widely varying widths.

Still another object of the invention is to provide such a portable scaffold in which all of the parts which contact the window or adjacent portions of the building are formed from or covered by resilient material, thereby preventing injury to the window or building.

Another object is to provide such a scaffold which will not fail through the loosening of parts.

Another object is to provide such a scaffold which when not in use as a scaffold is rollably supported in an upright position not only to facilitate movement of the scaffold from place to place but also to enable its use in transporting other articles.

Other objects and advantages of the invention will appear from the accompanying description and drawings in which:

Fig. 1 is a perspective view of a portable support or scaffold embodying the present invention.

Fig. 2 is an elevational view thereof taken from the side of the scaffold which faces the building when the device is in use.

Fig. 3 is a vertical, sectional view of the scaffold of the present invention in position for use, a portion of a window and adjoining building structure being shown to illustrate the manner in which the scaffold is held in place.

Fig. 4 is a horizontal sectional view on the line 4—4, Fig. 2.

Fig. 5 is a detailed sectional view on line 5—5 of Fig. 2 of one of the hooked arms by which the scaffold is supported.

2

Fig. 6 is a detailed view partly in section of a modification in which the hooked arms are made adjustable in length.

Fig. 7 is an enlarged fragmentary view of the adjustable screw-threaded connection by which the length of the hooked arms may be adjusted.

The support or scaffold of the present invention is similar to and constitutes an improvement on the support shown and described in my co-pending application, Serial No. 754,632 filed June

14, 1947, now Patent No. 2,492,598 issued December 27, 1949.

The device of the present invention differs from the device of the prior application in providing a stronger, more rigid scaffold

which is adapted for use with windows of any width and which may be equipped with adjustable means for adapting the support or scaffold for use with windows in which the sills are of greater or less depth than the average. The scaffold of

the present invention is also more easily transported, handled, and more quickly mounted for use. The scaffold of the present invention also has extensible arms to fit windows of varying depths and at the same time is free from the danger of failure through loosening of parts.

The support, indicated generally by the reference numeral 20, includes a body which comprises a bottom, indicated generally by the reference character 22, and a generally semi-cylindrical wall or shield 24. The bottom 22 comprises a

generally semi-circular plate 26 which is provided around its periphery with a depending flange 28.

A sheet 30 which is preferably formed of plywood, but may be of any other suitable non-metallic material, is provided on the upper surface of the metal plate 26. The sheet 30 extends to the edge of plate 26 on all sides thereof and is secured to the plate by suitable means such as a plurality of spaced rivets 32. The bottom

22 is reinforced by a plurality of transversely extending T bars 34 which are provided on the under side of the metal plate 26 and are attached thereto, preferably by welding or riveting.

The semi-cylindrical shield or wall 24 of the scaffold 20 extends vertically upward from the bottom 22 and the bottom edge of the wall is attached to the depending flange 28 of the metal plate 26 by welding or other suitable means.

The edges of the shield or wall 24 above the bottom 22 are rolled as shown at 36 and a hand hole 38 is provided in the center of the wall adjacent the top edge thereof. In order to give an occupant freedom of movement it is preferred to

round off the junction of the front vertical edges 40 of the wall 24 and the top edge thereof to provide a curved portion 42 at each side thereof.

In order to reduce the weight of the support or scaffold of the present invention, it is preferred to form the metal bottom plate 26 and the shield or wall 24 of aluminum although other materials may be used if desired. The wall 24 is reinforced, however, intermediate its top and bottom by a metal strap or band 44 which extends around its outside and is secured thereto by suitable means such as a plurality of spaced rivets 46. The band 44 is of greater length than the outside periphery of the wall 24 and the ends 48 of the band 44 project outwardly from the vertical edges 40 of the shield 24 in spaced, parallel relation to each other and are adapted to support the holding or clamping device with which the scaffold 20 is provided. Each of the free ends 48 of the band or strap 44 is shown as being provided with a rubber pad 50 which fits along the lower edge and the lower portion of the outer face of the end 48. The rubber pads 50 are preferably secured to the strap ends 48 by cementing and they serve to protect the woodwork against accident or marring.

As shown in Figs. 1-5, the support or scaffold 20 is provided with pivoted arms 54 the ends of which are bent back as indicated at 56 to form hooks 56. Each of the pivoted arms 54 is provided at its end opposite the hook 56 with an integral extension 58 which extends substantially at right angles to the main portion of the arm 54 and to the same side of the arm as the hook 56. At the outer end of the extension 58 on each of the arms 54 there is provided a screw threaded hole which is adapted to receive one end 60 of a cross rod 62. The cross rod 62 extends freely through aligned holes in the ends 48 of the band 44, the threaded end portions 60 projecting slightly beyond the band ends 48 so that the arms 54 threaded thereon will be adjacent the ends. The threads on the end portions 60 are arranged oppositely to prevent accidental unfastening of one of the arms 54.

Between the band ends 48 the cross rod 62 carries a pair of supporting rollers 66. Each of the rollers 66 is preferably formed of rubber or other somewhat resilient material and is mounted for free rotation on the rod 62 adjacent the inside of one of the band ends 48. The rollers are held against lateral displacement on the cross rod 62 by the band ends 48 and by fixed washers or collars 68 one of which is secured to the rod 62 on the inwardly facing side of each of the rollers.

The free ends of the pivoted arms 54 beyond the hooks 56 are preferably enlarged to provide blocks 70 which are elongated transversely of the arms 54 and may conveniently be cylindrical. Each of the blocks 70 is provided with a longitudinally extending bore, and a second cross rod 72 is provided which passes through the bores in the blocks 70 and is secured in place therein by nuts 74 mounted on the threaded ends of the rods 72. As a result of the joining of the blocks 70 by the cross rod 72, the pivoted arms 54 which normally occupy a depending vertical position under the influence of gravity are movable in unison. The cross rod 72 further serves to prevent either of the arms 54 from being inadvertently turned so as to become unscrewed from the cross rod 62. Each of the arms 54, including the block 70 on the end thereof, is preferably provided with a closely fitting coating or cover 76 of rubber or other resilient plastic material, the purpose of which will be made clear hereinafter.

Adjacent each end of the straight front edge of the bottom 22 of the scaffold 20 there is provided

a roller 78 which is preferably formed of rubber or other suitable resilient material. Each of the rollers 78 is rotatably mounted on a pin 79 projecting outwardly from the opposite sides of the bottom 22 and located to position these rollers 78 to project beyond the depending flange 28.

In Fig. 3 of the drawing the scaffold 20 of the present invention is shown in position in a window as it would be used. The window casing shown in the drawing is of substantially conventional construction for a sliding sash window, and is shown as comprising a sill 84 which is provided with an inner stop 86, and side jams 88 carrying the usual inner and outer stops 90 and 92 which form the vertical guideways for the sash (not shown). The window casing is mounted in the usual window opening provided in the frame of a building which is shown as also provided with an outside wall 94, an inside wall 26 and horizontal trim members 98 and 100. The scaffold 20, which resembles a half-barrel, is supported on the outside of the building by means of the rollers 66 which rest upon the window sill 84 and is held in place by the engagement of the curved portions or hooks 56 of the pivoted arms 54 with the stop 86 on the inner portion of the sill 84.

In placing the support or scaffold 20 in position for use, the scaffold is lifted into an opened window with the open side of the support facing downwardly. This may be conveniently done while facing the open side of the scaffold 20 by grasping the wall 24 with one hand by the hand hole 38, grasping with the other hand the cross rod 62, and tilting the scaffold so that the bottom 22 thereof is substantially vertical. In this position the pivoted arms 54 extend downwardly substantially parallel with the bottom 22 and the supporting rollers 66 may be placed on the stop 86 or the sill 84 of the window and thus bear the weight of the scaffold. The scaffold 20 may then be rolled outwardly through the window on the rollers 66 until the position of the arms 54 and rollers 66 shown in Fig. 3 is reached with the hooks 56 of the pivoted arms 54 engaging the stops 86. The scaffold may then be permitted to assume the vertical position illustrated in Fig. 3, in which position it is ready for occupancy.

As will be seen from Fig. 3, when the scaffold 20 is mounted outside a window, it is firmly secured in place and there is no danger of its becoming unfastened while in use. However, when it is desired to remove the support 20 from its position outside the window, it is merely necessary to grasp the support by the hand hole 38 and pull inwardly. This causes tilting of the support so that the bottom 22 is in substantially vertical position and the support may then be rolled inwardly on the rollers 66, the hooks 56 and blocks 70 thereby becoming disengaged from the stop 86. The support may then be lifted from the window sill by simultaneously grasping the cross rod 62 with the other hand.

The rubber or other resilient coating of the arms 54 and blocks 70 and the provision of the resilient rollers 66 and 78 prevents marring of the surfaces of the window frame or of the side of the building by the scaffold. The rollers 78 which project outwardly and downwardly from the straight edge of the scaffold 20 also permit the scaffold to be rolled along the floor to the window with which it is to be used. In order to have the scaffold maintain a vertical position when standing on the floor, a caster 83 is provided under the

bottom 22 adjacent the rear or semi-circular edge of the bottom plate 26.

Since the scaffold 20 is held in position by the hooks 56 of the pivoted arms 54 engaging with the stops 86, the support may be used equally well with windows of any width. The construction shown in Figs. 1-5 of the drawing will be usable with most windows. Occasionally, however, windows with extremely deep or shallow sills are encountered and it may therefore be desirable to provide adjustment for the length of the pivoted arms 54. A convenient and satisfactory adjusting means is, therefore, illustrated in Figs. 6 and 7.

In Figs. 6 and 7 the block 106 which corresponds to the extension 58 of the pivoted arms 54 in the form of the invention shown in Figs. 1-5, is shown as being threadedly mounted at one end on an end 60 of the cross rod 62. At its free end the block 106 is provided with a threaded bore 108 in a plane perpendicular to the axes of the rod 62 within which there is screwed a threaded stem 110 formed integrally with an arm 112 which is similar to the arm 54 and is provided with a bent portion 114 forming a hook and a block or enlarged portion 116 at its tip which may be identical with the blocks 70. As in the case of the pivoted arms 54 and the blocks 70, the arm 112 and blocks 116 are provided with a rubber or other resilient plastic coating 118. On each side of each block 106 there is threadedly mounted on the stem 110 a lock nut 120, which when tightened against the block 106 prevents rotation of the stem and the arm 112. The blocks 116 of the arms 112 are connected by a cross rod 72 held in place by nuts 74 in the same way as the blocks 70.

The adjustment permitted by the threaded construction shown in Figs. 6 and 7 makes it possible to change the effective length of the arms 112 so as to allow the use of the support or scaffold 20 with windows in which the sills are deeper or narrower than ordinary windows. Also by the threaded connection between the arms 112 and blocks 106, there is no danger of failure of the scaffold because of loosening of the lock nuts.

When the scaffold 20 is mounted outside a window, the bottom 22 of the scaffold is arranged at a convenient height so that a person standing thereon may readily wash the window panes, paint the sash and exterior window trim, putty or reglaze the windows, or apply storm windows or screens. The scaffold may be entered by merely stepping over the window sill onto the bottom 22 which is of sufficient size to permit tools and materials to be placed thereon. The semi-circular wall of the scaffold surrounds the occupant and eliminates any danger of stepping off of the scaffold while working. The wall is rigidly attached to the bottom and it is reinforced by the strap or band 44 which passes around its exterior. As previously mentioned, when the scaffold is occupied, it is impossible to disengage it from the window and it cannot become loose and fall.

From the foregoing it will be seen that the present invention provides an improved, simple and safe scaffold or support which is easily portable and which may be readily placed in position for use or removed from a window. The scaffold is ruggedly constructed and a minimum number

of parts are employed, thereby reducing the cost of manufacture and maintenance.

I claim:

1. A portable, removable window scaffold of the character described comprising a rigid body having a bottom and a side wall rising from said bottom and fixed thereto, said side wall being provided with an opening at one side, a metal arm rigidly secured to said body on each side of said opening and projecting horizontally therefrom in substantially the same direction, a supporting roller rotatably carried by each of said arms, said rollers being generally coaxial and adapted to rest on a window sill, a pair of rigid arms, each being bent adjacent its free end to form a hook adapted to engage on the inner side of said window sill to secure said scaffold in position outside said window, a block pivotally supported on each of said first-mentioned arms and having a threaded bore, and each of said last-mentioned arms having at its other end an extension threadedly and adjustably secured in the bore of one of said blocks.
2. A portable, removable window scaffold of the character described comprising a rigid body having a bottom and a side wall rising from said bottom and fixed thereto, said side wall being provided with an opening at one side, a metal arm rigidly secured to said body on each side of said opening and projecting horizontally therefrom in substantially the same direction, a rod extending between and secured to said arms, a supporting roller rotatably mounted on each end of said rod adjacent said arms and being of a size to project downwardly from said arms to rest on a window sill, and an arm mounted on each end of said rod adjacent the corresponding one of said first arms to swing about the axis of said rod, each of said last arms being provided with a bent portion adapted to engage on the inner side of said window sill to secure said scaffold in position outside said window.
3. A portable, removable window scaffold of the character described comprising a rigid body having a bottom and a side wall rising from said bottom and fixed thereto, said side wall being provided with an opening at one side, a metal arm rigidly secured to said body on each side of said opening and projecting horizontally therefrom in substantially the same direction, a horizontal rod journaled at its opposite ends in said arms and having its ends projecting outwardly therefrom, a supporting roller journaled on each end of said rod adjacent and between said arms and being of a size to project downwardly from said arms to rest on a window sill, and a pair of arms fixed to the ends of said rod projecting from said first arms, each of said last arms being provided with a bent portion adapted to engage on the inner side of said window sill to secure said scaffold in position outside said window.
